UNITED STATES PATENT OFFICE.

JOHN I. STEEN, OF WAUKEGAN, ILLINOIS, ASSIGNOR TO TRIPLE METALS CORPORATION, OF WAUKEGAN, ILLINOIS, A CORPORATION OF ILLINOIS.

ATTACHMENT FOR WASHBOILERS.

1,392,460.

Specification of Letters Patent. Patented Oct. 4, 1921.

Application filed October 6, 1920. Serial No. 415,023.

To all whom it may concern:

Be it known that I, JOHN I. STEEN, a citizen of Finland, residing at Waukegan, county of Lake, and State of Illinois, have 5 invented certain new and useful Improvements in an Attachment for Washboilers, of which the following is a specification.

This invention relates to domestic laundry devices, and has among its objects the 10 provision of an attachment for wash-boilers of the usual construction and size, whereby a combined wash-boiler and washing machine of inexpensive construction and great efficiency will be furnished for 15 facilitating the washing of clothes and the like, by subjecting them to the cleansing action of a constant current or circulation of hot water or soap-suds and steam.

A further object is to furnish a wash- 20 boiler attachment of such construction as to adapt it for use in wash-boilers of the standard size, and so that parts thereof may be detached from other parts and the entire device compactly packed for shipment, 25 thereby rendering it unnecessary to ship with the attachment a bulky boiler.

Still another object is to provide an attachment of the above named general character, by means of which the articles being 30 washed can be readily removed in bulk from the boiler and so held, if desired, to permit them to drain.

A still further object is to provide means for concentrating the heat of the burners 35 of a stove or gas plate and for applying it in such a way to the attachment, that steam within the boiler will be quickly generated, and together with hot water will be discharged on the garments or articles 40 to be percolated therethrough.

Other objects and advantages of the invention will be apparent from the following description and explanation.

The invention consists in certain peculiarities of the construction, novel arrangement, combination and operation of the parts thereof as will be hereinafter more fully set forth and specifically claimed.

In the accompanying drawing, which 50 serves to illustrate an embodiment of the invention—

Figure 1 is a vertical sectional view of the attachment showing it located in a wash-boiler ready for use.

Fig. 2 is a horizontal sectional view taken 55 on line 2—2 of Fig. 1 looking in the direction indicated by the arrows.

Like numerals of reference refer to similar parts in both views of the drawing.

The numeral 5 designates a wash-boiler 60 of the usual flat bottomed construction and of the standard size. This boiler is by preference provided at the upper portion of each end thereof with a handle 6 for lifting or moving the vessel from place to 65 place, and is supplied with a lid or cover 7 adapted to fit or tightly close the upper portion thereof.

The attachment comprises a hollow base, 70 which is designated as a whole by the numeral 8, which is of a size and shape to fit snugly within the boiler and to normally rest on the bottom or floor of the latter. The base 8 includes the flat horizontally disposed plate 9 which has its edges downwardly and outwardly deflected as at 10 to 75 rest on the bottom of the boiler near the vertical walls thereof and in such a manner as to maintain the horizontally disposed portion of the base 8 at a slight distance 80 from the walls of the boiler.

As is clearly shown in Fig. 1 the deflected portion 10 of the base is provided in its lower edge with a series of spaced openings 11 for the passage of water. By this arrangement it is obvious that a hollow base or chamber is provided for the generation 85 of steam and for the circulation therethrough of water.

The plate 9 of the base 8 is provided on 90 its lower surface with a pair of spaced annuli 12 which are so located with respect to one another as to each surround a burner of the gas stove or gas plate on which the boiler may be located when using the same. 95 Each of the annuli or ring-like bands 12 is of a depth equal to that of the deflected portion 10 of the plate 9 of the base, which deflected portion and said band-like members or annuli 12 will afford a strong support for the plate 9 of the base. Each of the annuli 12 is provided in its lower edge 100 with a plurality of spaced recesses or cut-outs 13 for the passage of water and steam. The plate 9 of the base is provided concentrically with respect to each of the annuli 12 with an upwardly extended tube 14 which communicates with the cavities 105

formed by the annular members 12 as will be readily understood by reference to Fig. 1 of the drawing.

- Horizontally and diametrically located in 5 the upper portion of each of the tubes 14 is a rod 15 which has on each of its ends externally of the tube 14 a head 16, which heads are slightly spaced from the walls of the tube on which it is mounted. Detachably 10 mounted on each of the tubes 14 is an upwardly tapered pipe 17 for the discharge of water and steam. The upper end of each of the pipes 17 is closed and by preference is provided with an upwardly extended loop 15 or hook 18 through which a pole may be extended longitudinally with respect to the boiler when it is desired to remove the attachment from the latter. The upper end of each of the pipes 17 is provided with a 20 series of openings 19 which are arranged in staggered relation to one another and are by preference produced by punching portions 20 of the metal out of which the pipes are made inwardly yet so that the upper 25 edge of each of said portions will be connected to the pipes. By this arrangement it is evident that each pipe 17 will be provided in the upper portion of its walls with a plurality of outlets 19 for the passage of 30 steam and water and that each outlet will have an inwardly and downwardly disposed deflector 20 to cause the steam and water as the same rises in the pipe 17 and passes through the openings 19 to be deflected or 35 discharged downwardly in jets around each of the pipes. The plate 9 of the base 8 is provided at about its juncture with the downwardly deflected part 10 with a number of upwardly extended brackets 21 on the 40 upper portions of which is mounted and secured a rail 22 which coincides with the outlines of the base when viewed from above and together with the base and brackets 21 will provide a tray or basket-like container 45 for the articles to be washed, which of course, after the attachment has been placed in the boiler as shown in Fig. 1, will be placed on the base 8 within the railing thereof. 50 Again referring to the pipes 17 it will be seen and understood by reference to Fig. 1 that the lower portion of each pipe is provided with a bayonet slot 23 on opposite sides thereof to receive and engage the rods 55 15 inwardly of their heads 16, which rods are mounted on the tubes 14 as above set forth.
- By this construction it is obvious that the 60 pipes 17 can be readily attached to the tubes 14 in such a way that the attachment can be easily removed even when loaded with clothes from the boiler by means of the hooks or loops 18 on the pipes 17 through which a pole or other device may be ex-

tended for lifting the attachment out of the boiler. By detachably mounting the pipes 17 on the tubes 14 it is manifest that said pipes can be readily released from the tubes and placed in a horizontal position on the base 8 within the railing 22 when the attachment will be in such condition as to be compactly packed for shipment.

The operation of the device is as follows: Assuming that the parts are placed in the boiler as shown in Fig. 1 of the drawings, it is obvious that a sufficient quantity of water may be supplied to the boiler and the clothes or articles to be washed are placed therein so as to rest on the base 8 of the attachment and to partially fill the boiler. The thus equipped boiler can then be placed on a stove or gas plate, when it will be understood that the annular members 12 can be located so as to surround a pair of the burners of the stove or said plate thus utilizing the heat from said burners in direct application to the bottom of the boiler circumscribed by the members 12, which arrangement will cause the water encompassed by the members 12 to quickly become heated and ascend in the form of hot water and steam through the pipes 17 from the upper portions of which the same will be discharged in all directions through the openings 19 so as to fall on top of the clothes or garments through which the water will percolate to again enter the openings 13 of the members 12 when the same operation will be continued as long as sufficient heat is applied to the boiler.

Having thus fully described my invention, what I claim as new and desire to secure by Letters Patent is—

A device of the class described, consisting of a base having its edges downwardly deflected therefrom and adapted to rest on the bottom of a boiler thereby forming a chamber between said base and the bottom of the boiler, said deflected portion of the base having spaced recesses therein, a pair of spaced upright tubes mounted on the base at a distance from its edges in communication with said chamber, a perforated annulus mounted on the lower surface of the base around each of said tubes and each adapted to rest on the bottom of the boiler, a pipe interlockingly and detachably connected at its lower end to each of said tubes and having its upper end closed and below said end a plurality of openings, an inwardly and downwardly disposed deflector located within each of said pipes above each of the openings in the upper part thereof, a hook or loop on the upper end of each of said pipes, and a horizontally disposed rail supported by the base at a distance above the same along its edges.

JOHN I. STEEN.
